UNITED STATES PATENT OFFICE.

THOMAS L. STONE, OF NEWARK, NEW JERSEY, ASSIGNOR TO HAMPDEN GLAZED PAPER & CARD COMPANY, OF HOLYOKE, MASSACHUSETTS, A CORPORATION OF MASSACHUSETTS.

DESIGN FOR PAPER.

Application filed January 12, 1925. Serial No. 12,029. Term of patent 14 years.

To all whom it may concern:

Be it known that I, THOMAS L. STONE, a citizen of the United States, residing at Newark, in the county of Essex and State of New Jersey, have invented a new, original, and ornamental Design for Paper, of which the following is a specification, reference being had to the accompanying drawing, forming a part thereof.

The figure is a view of a piece of paper embodying my new and original ornamental design.

I claim the ornamental design for paper as shown.

THOMAS L. STONE.
